CLAIM

The ornamental design for a earring, as shown and described.

DESCRIPTION

FIG. 1 is a front, right side, bottom perspective view of the earring;

FIG. 2 is a front elevational view;

FIG. 3 is a right side elevational view thereof;

FIG. 4 is a left side elevational view thereof;

FIG. 5 is a top plan view thereof; and,

FIG. 6 is a bottom plan view thereof.

The broken line portions are shown for environmental purposes and form no part of the claimed design.

Because a portion of the article is not solid, the remote side of the article is normally visible through the fore side of the article in the side view but is not shown in the figures for ease of illustration.
